United States Patent Office.

B. W. COLLIER, OF OXFORD, MISSISSIPPI.

Letters Patent No. 70,529, dated November 5, 1867.

IMPROVEMENT IN COMBINED TOOL.

The Schedule referred to in these Letters Patent and making part of the same.

TO ALL WHOM IT MAY CONCERN:

Be it known that I, B. W. COLLIER, of Oxford, in the county of Lafayette, and State of Mississippi, have invented a new and useful Combined Tool; and I do hereby declare the following to be a full, clear, and exact description of the same, reference being had to the accompanying drawings, forming part of this specification, and in which—

Figure 1 is a side view of my invention.

Figure 2 represents one edge of my improved tool, and

Figure 3 the opposite edge.

Similar letters of reference indicate corresponding parts in the several figures.

This invention combines in one instrument a pair of pliers, a pair of clippers, a file, a burnisher, a hammer, several punches, three or four wrenches, a saw-set, a screw-driver, a scraper, and a set of holes for straightening wire, nails, &c.

In order that others skilled in the art to which my invention appertains may be enabled to make and use the same, I will proceed to describe it in detail.

In the drawings, A A represent the jaws, and A' A' the handles of a pair of pliers. On one side of the jaws raised lips or knife edges C are provided, shutting against each other so as to form a pair of clippers, for the purpose of clipping tin, sheet iron, wire, &c. The back of one of the jaws is cut into a file, F, and the back of the other formed for a burnisher, B, and a hammer, H. The handles are made in the shape shown in the drawing, and at p p p one of them is provided with a set of pins, of different sizes, projecting when the instrument is shut into corresponding holes on the other side, and forming a set of punches. Near the same point a series of holes, h h h, of different sizes, is made in the stout handle for the purpose of straightening wires, nails, pins, &c., &c. At another point in the handle a set of three or more wrenches, W W W, is provided, as shown in the drawings. Near the extremity of the handle a saw-set, S, is cut in one edge of it, and the handle finally terminates in a claw, K. The end of the opposite handle is formed and tempered for a screw-driver, D, and above this it is made, at G, with edges somewhat sharp to fit it for scraping plates of iron, wire, &c., &c.

The whole instrument, thus formed and adapted for so many different purposes, is as compact, simple, and neat, and almost as cheap as an ordinary pair of pliers. It may be made so small, if necessary, as to be easily carried in the pocket.

Having thus described my invention, what I claim as new, and desire to secure by Letters Patent, is—

The instrument above described, having the parts combined and arranged substantially as and for the purposes specified.

B. W. COLLIER.
